WIG STAND HOLDER FOR A VEHICLE SEAT

Palmer B. Peters, 2825 Knodel St.,
Torrance, Calif. 90501

Filed Nov. 7, 1973, Ser. No. 413,530

Term of patent 14 years

Int. Cl. D28—03

U.S. Cl. D86—10 A

Fig. 1.

Fig. 2.

Fig. 3.

Fig. 4.

Fig. 5.

Fig. 6.

Fig. 7.

FIG. 1 is a perspective view of a wig stand holder for a vehicle seat showing my new design;
 FIG. 2 is a left side elevational view;
 FIG. 3 is a right side elevational view;
 FIG. 4 is a rear elevational view;
 FIG. 5 is a front elevational view;
 FIG. 6 is a top plan view; and
 FIG. 7 is a bottom plan view thereof.

I claim:

The ornamental design for a wig stand holder for a vehicle seat, substantially as shown.
